**SNAP FASTENER CONNECTOR FOR A FISH
HOOK OR THE LIKE**

Shigemi Imai, 8 1-chome, Kumochibashi Dori,
Fukiai-ku, Japan

Filed Mar. 25, 1966, Ser. No. 1,639

Term of patent 14 years

(Cl. D22—29)

FIG. 1.

FIG. 2.

FIG. 3.

FIG. 4.

FIG. 5.

FIG. 6.

FIGURE 1 is a top plan view of a snap fastener connector for a fish hook or the like embodying my new design;

FIGURE 2 is a bottom plan view thereof;

FIGURE 3 is a side elevational view thereof;

FIGURE 4 is a side elevational view of the side opposite that shown in FIGURE 3;

FIGURE 5 is a front end view thereof; and,

FIGURE 6 is a rear end view thereof.

The characteristic feature of my design resides in the provision of a snap fastener connector for a fish hook or the like having a narrow end formed as a round eye and a pair of elongated side legs extending in diverging fashion from the narrow end to a wide end, one of said side legs being longer than the other so that one corner of the wide end is formed with an acute angle and so that the arm extending across the wide end runs angularly from one side leg to the other all as shown on the drawing.

I claim:

The ornamental design for a snap fastener connector for a fish hook or the like, as shown and described.
